UNITED STATES PATENT OFFICE.

ELLA NEILSON GAILLARD, OF NEW YORK, N. Y., ASSIGNOR OF ONE-FOURTH TO
REBECCA M. HALLENBACK AND AGNES HALLENBACK, BOTH OF NEW YORK, N. Y.

WOVEN FABRIC.

1,105,503.

Specification of Letters Patent. Patented July 28, 1914.

Application filed September 30, 1913. Serial No. 792,670.

To all whom it may concern:

Be it known that I, ELLA NEILSON GAILLARD, a citizen of the United States, residing at New York, in the county of New York and State of New York, have invented certain new and useful Improvements in Woven Fabrics; and I do hereby declare the following to be a full, clear, and exact description of the invention, such as will enable others skilled in the art to which it appertains to make and use the same.

This invention comprehends improvements in woven fabrics and has for its primary object to provide a strong and durable fabric of this nature which is especially adapted for use as a shoe string, corset lace, et cetera.

Another object of the invention is to provide a narrow woven fabric of non-elastic thread, which shall be so woven as to be able to withstand much wear and still be fine enough to form a shoe string and laces of various kinds.

With these and other objects in view as will become more apparent as the description proceeds, the invention consists in certain novel features of construction, combination and arrangement of parts as will be more fully hereinafter described and claimed.

For a complete understanding of my invention, reference is to be had to the following description and accompanying drawings, in which the figure is an enlarged diagrammatic view, illustrating a cross section of the fabric.

My improved fabric consists of the face warp-threads 1, the back warp-threads 2, face weft-threads 3, back weft-threads 4, gut or stuffer warp-threads 5, and binder warp-threads 6. The face and back warp-

threads are preferably arranged in opposed sets with four threads in each set. The gutting or stuffing warp-threads are interposed between corresponding sets of face and back warp-threads, as clearly shown in the drawings, and the binder-threads separate each two sets of face and back warp-threads. The weft-threads are interwoven first with the face warp threads and then with the back warp threads, or vice versa. The face weft-threads pass behind the binder-threads and the back weft-threads pass in front of the binder-threads and thus the two plies of the fabric are stitched together.

From the foregoing description taken in connection with the accompanying drawings, it will be seen that I have formed a novel woven fabric which is suitable for different kinds of laces which will wear very well and which is strong and durable.

Having thus described my invention, I claim:—

A fabric composed of face warp-threads arranged in sets, back warp-threads arranged in sets and opposed to the face warp-threads, stuffing warp-threads interposed between corresponding sets of face and back warp-threads, face and back weft-threads interwoven first with the face warp threads and then with the back warp threads or vice versa, and binder-threads, the face weft-threads passing behind the binder-thread and the back weft-threads passing in front of the binder-threads.

In testimony whereof I affix my signature in presence of two witnesses.

ELLA NEILSON GAILLARD.
